(57) **CLAIM**

The ornamental design for insulation jacketing as shown and described.

DESCRIPTION

FIG. 1 is a perspective view of a first embodiment of insulation jacketing showing my new design;

FIG. 2 is a front view thereof, the rear view being a mirror image thereof;

FIG. 3 is a left side view thereof, the right side view being a mirror image thereof;

FIG. 4 is a detailed view of section 4 taken from FIG. 1;
FIG. 5 is a section view taken from the detailed view of FIG. 4 taken along lines 5-5.

FIG. 6 is a perspective view of a second embodiment of insulation jacketing showing my new design;

FIG. 7 is a front view thereof, the rear view being a mirror image thereof;

FIG. 8 is a left side view thereof, the right side view being a mirror image thereof;

FIG. 9 is a detailed view of section 9 taken from FIG. 6;

FIG. 10 is a section view taken from the detailed view of FIG. 9 taken along lines 10-10.

FIG. 11 is a perspective view of a third embodiment of insulation jacketing showing my new design;

FIG. 12 is a front view thereof, the rear view being a mirror image thereof;

FIG. 13 is a left side view thereof, the right side view being a mirror image thereof;

FIG. 14 is a detailed view of section 14 taken from FIG. 11;

FIG. 15 is a section view taken from the detailed view of FIG. 14 taken along lines 15-15.

FIG. 16 is a perspective view of a fourth embodiment of insulation jacketing showing my new design;

FIG. 17 is a front view thereof, the rear view being a mirror image thereof;

FIG. 18 is a left side view thereof, the right side view being a mirror image thereof;

FIG. 19 is a detailed view of section 19 taken from FIG. 15; and,

FIG. 20 is a section view taken from the detailed view of FIG. 19 taken along lines 20-20.

The evenly spaced broken lines shown in the figures illustrate portions of the Insulation Jacketing and form no part of the claimed design. The dot dash broken line indicates cutoff boundaries for enlarged detailed portion views and form no part of the claim.
